CAMEL COMPANY, OF CHICAGO, ILLINOIS, A CORPORATION OF ILLINOIS

DOOR ELEVATING MECHANISM

Application filed May 20, 1931. Serial No. 538,716.

This invention relates to operating mechanism for car doors and particularly for car doors having frictional engagement with a supporting track in their normal or lowered position and which are elevated to permit movement toward open and closed positions. It is among the objects of this invention to provide simple, rugged and inexpensive operating mechanism for car doors of the character set forth, in which said mechanism is utilized to elevate and move said door toward open and closed positions.

This invention comprises, further, the novel structure and combination of parts hereinafter described and more particularly pointed out and defined in the appended claims.

In the accompanying drawing

Figure 1 is a fragmentary elevation of a car door having the operating mechanism of the invention applied thereto.

Figure 2 is a vertical section on line 2-2 of Figure 1, the door being shown in lowered position.

Figure 3 is a view similar to Figure 2, the door being shown in elevated position.

Figure 4 is a horizontal section taken on line 4-4 of Figure 1.

In the preferred embodiment of the invention illustrated in the drawing there is shown a sliding car door 10, preferably of metal, having secured thereto at its lower corners brackets 11-11 provided with pads 12-12 by which frictional engagement and support of the door in its lowered position is established with a supporting track 13. This track is supported by means of a plurality of track brackets 14, one of which is shown in part in Figure 2 of the drawing upon a side sill of the car (not shown).

In order to slide the door toward open or closed positions it is necessary, first, to elevate the door above the track. For this purpose the operating mechanism of this invention is utilized. The operating mechanism

comprises, preferably, a substantially inverted V-shaped member 15 provided at each end thereof with a longitudinally extending trunnion 16. The trunnions are adapted to be journaled in bearings 17 in alignment with said journals provided in the brackets 11-11. The journals 16 are preferably provided on cap members 18 secured to the opposite ends of the member 15. These cap members are provided, additionally, with longitudinally extending lugs 19 spaced in the normal or lowered position of the door from a longitudinally extending flange 20 formed on the brackets 11-11 for a purpose hereinafter indicated.

As noted above the member 15 is preferably of inverted V-shaped construction and the legs of the V are preferably undercut as indicated at 21-21. Seated within the member 15 is a plurality of rolling elements represented in the present embodiment of the invention as balls 22-22. These balls as clearly shown in Figures 2 and 3 of the drawing contact at spaced points with the undercut shoulders 21-21 formed on the member 15. It is clear from this construction that the member 15 provides a runway for the balls 22-22 which are adapted to travel relative to the track and the member.

For the purpose of elevating the door to permit sliding movement thereof relative to the track a bracket member 23 is secured as by means of rivets to the member 15. Positioned within the bracket member 23 is a base 24 of a link 25. This base of the link is retained for pivotal and rocking movement in the bracket 23 by means of the overlapping fingers 26. As clearly indicated in Figure 1 of the drawing, in order to facilitate the rocking movement of the link which may occur, the base thereof is preferably rounded as shown at 27. The link extends upwardly from its engagement with the bracket member 23 and is provided with a head portion 28 adapted to extend through an opening 29

formed in an operating lever 30. The operating lever is pivotally mounted at one end thereof upon a boss 31 formed integrally with a bracket plate 32 riveted to the door. The head portion 28 is provided with a downwardly extending flange or lip 33 by means of which disengagement with the operating lever 30 is avoided.

With the construction set forth above the operation of the door will become apparent. Assuming the door to be in the position illustrated in Figure 1 with the door in its normal or lowered position in frictional engagement with the supporting track 13, it is necessary, in order to move the door from such position, to grasp the free end of the operating lever 30 and exert a downward pull thereon. The downward movement of said lever will be communicated through the link 25 to the bracket member 23 which, because of its connection with the member 15, will cause said member to be rotated upon the balls 22-22 as fulcrums about the pivotal connection established between said member and the door by means of the trunnions 16-16 journaled in the bearings 17-17 formed in the brackets 11-11 secured to the door. It is observed that the journals 16-16 are located in eccentric position with regard to the longitudinal axis of the member 15. In view of this fact the rotation of the member 15 will effect a lifting movement of the door. When the door has been raised it may then be moved to the desired position by exerting a pull or thrust against the operating lever. It should be noted that in the rotating movement of the member 15 in the bearings 17 provided in the door brackets the longitudinally extending lugs 19 rotate with the member 15 until engagement between said lugs and the longitudinally extending walls 20 formed on the brackets occurs. By this construction positive means to limit the rotation of the member 15 is provided.

It is apparent that numerous changes and modifications in the structural details of the embodiment disclosed may be made without departing from the spirit of this invention. It is intended that all such modifications and changes are included within the invention which is to be limited only by the scope of the claims appended hereto.

We claim:

1. Door elevating mechanism comprising, in combination, a member eccentrically pivoted to said door, rolling means seated in said member and having horizontal movement relative thereto, a lever pivotally supported on said door and means including a link connecting said member and said lever, whereby movement of said lever is communicated to said member to elevate the door.

2. Door elevating mechanism comprising, in combination, a lever pivotally mounted upon said door for movement in a substan-

tially vertical plane, a longitudinally extending substantially inverted V-shaped member eccentrically pivoted at its ends to said door for transverse oscillation relative thereto and providing a runway, balls movable relative to said member positioned in said runway and a link connecting said lever and said runway capable of transmitting the coplanar movement of said lever into transverse movement of said member about the balls as fulcrums.

3. Door elevating mechanism comprising, in combination, a lever pivotally mounted upon said door for movement in a substantially vertical plane, a longitudinally extending substantially inverted V-shaped member eccentrically pivoted at its ends to said door for transverse oscillation relative thereto and providing a runway, spaced shoulders provided in said runway, balls movable relative to said member positioned in said runway in engagement with said shoulders and a link connecting said lever and said runway for the purpose set forth.

4. In door elevating mechanism, in combination, a lever pivotally mounted upon said door, a member pivoted eccentrically to said door, a bracket secured to said member and a link having a base portion seated in said bracket, said link being connected to the lever.

5. In door elevating mechanism, in combination, a lever pivotally mounted at one end thereof upon said door, said lever having an opening intermediate the ends thereof, a member pivoted eccentrically to said door, a bracket rigidly secured to said member and a link provided with a head portion and a base portion connecting said lever and said member, said head portion extending loosely through the opening in the lever and said base portion being loosely seated in said bracket.

6. In door elevating mechanism, in combination, a lever pivotally mounted at one end thereof upon said door, said lever having an opening intermediate the ends thereof, a member pivoted eccentrically to said door, a bracket rigidly secured to said member and a link provided with a head portion and a base portion connecting said lever and said member, said head portion extending loosely through said opening in the lever and being provided with a flange establishing interlocking engagement with the lever, said base portion being loosely seated in said bracket.

7. In door elevating mechanism, in combination, a lever pivotally mounted upon said door, a casting secured adjacent each lower corner of the door provided with aligned bearings and a wall positioned forwardly of said bearings, a member extending between said castings provided with eccentric trunnions journaled in said bearings, said member including a runway, rolling means seated in said runway adapted to roll upon a supporting track secured below said door, a lug

extending from each end of said member in spaced overlapping relationship with said walls, a link connecting said lever and said member, whereby pivotal movement of said lever will effect transverse movement of said member, the latter movement being limited by engagement of said lugs and said walls.

5 Signed at Chicago, Illinois, this 18th day of May, 1931.

10 WILFRED A. BEAUCHAMP.
AXEL WASBERG.
